UNITED STATES PATENT OFFICE.

HORATIO G. GILLMOR, OF WASHINGTON, DISTRICT OF COLUMBIA.

RAIL-ANCHOR.

1,206,836.

Specification of Letters Patent.

Patented Dec. 5, 1916.

Application filed April 30, 1915. Serial No. 24,968.

To all whom it may concern:

Be it known that I, HORATIO G. GILLMOR, a citizen of the United States, residing at Washington, in the District of Columbia, 5 have invented a new and useful Improvement in Rail-Anchors, of which the following is a specification accompanied by drawings.

This invention relates to devices known 10 as rail anchors, rail stays or anticreepers and one of its objects is to form a simple device which will prevent longitudinal movement of the rails of railways.

Another object of the invention is to provide 15 against rendering the device inoperative by reverse movement of the rail or by the effects of vibration.

To the accomplishment of these objects and such others as may hereinafter appear, 20 as will be readily understood by those skilled in the art, the invention comprises a rail anchor embodying the features of construction, the combination of elements and arrangement of parts having the general 25 mode of operation as hereinafter described and claimed.

The preferred embodiment of the invention is shown in the accompanying drawings, in which:—

30 Figures 1, 2 and 3 are, respectively, a plan view, a side elevation and a transverse elevation showing the device in operative position on the rail. Fig. 4 is a plan view showing the manner of applying the cross bar 35 and Figs. 5 and 6 are, respectively, a side elevation and an end elevation of the cross bar.

Similar letters apply to similar parts throughout the several views.

40 In the embodiment of the invention illustrated in the drawings, A is the rail, B a cross tie, C a tie plate and D a cross bar. The cross bar D is preferably rectangular in section and has one end turned back at 45 an angle to the body of the bar as at E to form an arm to engage the upper surface of the rail base flange. This arm is turned in the plane of the diagonal of the cross section of the bar as shown in Figs. 5 and 6 and presents two faces F and G, either of 50 which may engage the upper surface of the base flange of the rail. The other end of the bar is turned to approximately right angles to the face of the body of D, as at 55 H, and therefore has a face I parallel to the

face F of the arm E. The turning of the ends of the bar D as described forms two shoulders or abutments K and L adapted to engage the edges of the base flange of the rail and the distance between K and L is 60 made to slightly exceed the width of the base flange of the rail A. The tie plate C is provided with a projecting portion M, upon which is formed a portion N arranged to engage the bottom and one side of H below the rail and an upwardly turned portion O having a portion P arranged to engage H above the rail base and at the side opposite to that engaged by M. The tie plate C is flanged down at Q to form a tie abutment 65 engaging the vertical face of the tie, to take the thrust transmitted by the bar D to the tie plate when the rail moves in the direction of the arrow. The tie plate is further secured to the tie by spikes R.

70 To apply the device the cross bar D is placed on the rail with the face F of the arm E engaging the upper surface of the base flange at one side of the rail and the bar D transverse to the rail. In this position the 75 arm H has its face I, which is parallel to F, in contact with the bottom of the rail base. The arm E is so arranged that it is necessary to stress the arm and its connection to the bar in order to force D to a position in 80 which the face L of H will clear the edge of the rail base. A position of the bar D shortly before this is reached is shown in 85 Fig. 4. From this position the bar D is driven or otherwise forced transverse to the rail until L reaches the rail edge. The bar D is subject to some torsion while being so driven and as soon as H passes the edge of the rail it tends to turn toward the vertical position. While so turning the face F of 90 the arm E leaves the upper surface of the rail and this arm E assumes a position in which neither the face F nor the face G is in contact with the upper surface of the rail base. By forcibly turning H toward the 95 vertical however the face G of the arm E will be brought into contact with the upper surface of the rail base and the rail thus gripped on that side between the body of D and the arm E with the abutment K in contact with the edge of the rail base and the other abutment L on H in contact or nearly in contact with the other edge of the rail base. The tie plate C is then placed in position with the portion M engaging H at the 100 105 110

bottom and on the side below the rail and P engaging H at the other side above the rail base. The fit of the parts is preferably so arranged that the projecting portion M of C has to be forced into position by driving or otherwise on to the rail base so gripping the rail base between P and the body of C and at the same time forcing H to the vertical position and so setting up torsion on D and causing the base flange to be gripped at the opposite side of the rail between the arm E and the body of D.

The direction in which the rail tends normally to move is indicated by the arrow in Fig. 1 and this direction will be referred to as forward and the reverse direction as backward. It will be readily understood that if the rail tends to move forward the end carrying the arm E of the bar D will be carried forward with the rail and the other end of D will be held by the engagement of H with the portion M of the plate C. The cross bar will, therefore, move angularly or skew slightly on the rail A and this action will cause the crossbar D to grip the rail base edges between the abutments or shoulders K and L and so hold the rail against further forward movement. The thrust of the crossbar in the forward direction is taken up by the flange Q of the plate C engaging the face of the tie as illustrated in Figs. 2 and 3.

If the rail for any reason moves in the backward direction the crossbar D will be held at one end by the engagement of the portion P of the plate C with H while the other end of the bar D will be carried backwardly with the rail. The first effect of this movement will be to release the grip of the abutments L and K upon the rail edges; but, as the movement of the rail backwardly continues the cross bar will be skewed or moved angularly until the base edges are again gripped by these abutments K and L and the grip of the cross bar upon the rail sufficiently increased to withstand the forces tending to produce further backward movement of the rail. The movements of the rail will in this way be limited to such small movements as are necessary to bring about the skewing of the cross bar D necessary to produce the necessary grip of K and L upon the rail edges to meet and offset the forces tending to produce the movement. For the forward movement the resisting force is transmitted to the tie by the tie-engaging flange Q of the plate C and for the backward movement the resisting force is transmitted to the tie through the plate C and the spikes R.

Obviously some features of the invention may be used without others and the invention may be embodied in widely varying forms within the scope of the artisan.

Therefore without limiting the invention

to the construction shown and described or enumerating equivalents, I claim and desire to secure by Letters Patent:—

1. A device for preventing the creeping of rails comprising a bar extending transversely under the rail having the ends thereof provided with rigid abutments bearing against opposite edges of the rail base and at one end an arm adapted to engage and bear upon the upper surface of the rail base in longitudinal spaced relation to the transverse portion of said bar and means engaging the other end of said bar for holding the same in spaced relation to a tie.

2. A cross bar for rail stays having one end overturned to form with said bar a jaw adapted to grip the base of a rail at one side and the other end turned at approximately right angles to the body of said bar said jaw end and said right angle turned end being so related to the body of the bar that when the jaw engages the rail base at one side the right angled end may be brought into engagement with the edge of the rail base at the other side of the rail by rotation of said bar about an axis transverse to the rail.

3. A cross bar for rail anchors constructed of a rectangular bar having one end overturned in the plane of the diagonal of the section of said bar to form a jaw adapted to grip the rail base and the other end turned at approximately right angles to a face of said bar.

4. A cross bar for rail stays having at one end a jaw presenting a plurality of faces adapted to engage the upper surface of the rail base and at the other end an arm at approximately right angles to said bar.

5. A rail anchor comprising a cross bar constructed with a jaw at one end adapted to engage the rail base at one side of the rail and at the other end thereof an arm adapted to engage the edge of the rail base at the opposite side of the rail and a tie plate so engaging said arm as to maintain torsional stress in said bar.

6. A rail anchor comprising a cross bar constructed with a jaw at one end adapted to engage the rail base at one side of the rail and at the other end thereof an arm adapted to engage the edge of the rail base at the opposite side of the rail and means engaging said arm and the rail for maintaining torsional stresses in said bar.

7. An anticreeper comprising a cross bar constructed with a shoulder engaging the edge and an arm adapted to engage the upper surface of the rail base in spaced relation to the body of said cross bar at one side of the rail and a rigid abutment bearing against the edge of the rail base at the other side of the rail and means engaging a tie and acting upon the rigid abutment end of said cross bar for producing and maintain-

ing twisting forces in said cross bar and for holding said end in spaced relation to the tie.

8. A rail stay comprising a bar constructed with a rail base engaging jaw at one end and a rail edge engaging arm at the other end and a tie plate constructed so to engage said rail edge engaging arm as to produce and maintain torsional stresses in said bar 10 and to hold said arm out of contact with the tie.

9. A device for preventing the creeping of rails comprising an element constructed with an arm engaging the upper surface of 15 one side of the rail base at one side of said element and an arm engaging the edge of the other side of the rail base and a part arranged to engage the upper surface of 20 the rail base and said arm at one side of said arm and the under side of the rail base and said arm at the other side of said arm.

10. A rail anchor comprising a rail engaging and gripping element constructed with 25 rigid abutments to engage and clamp the opposite edges of a rail base and at one end an arm in longitudinal spaced relation to the body of said element adapted to engage the upper surface of the rail base and means 30 engaging the end of said element opposite to said arm and the tie for holding said end in spaced relation to the tie.

11. An anticreeper comprising a transverse element constructed to engage the edge 35 of the rail base at one side and the top and bottom of the rail base at the other side and a part so engaging a tie and said element that movement of the rail will produce a skewing action and a torsion in said element 40 and thereby increase the grip of said element upon the rail.

12. A device for limiting the longitudinal movement of rails in either direction comprising a transverse rail gripping part engaging opposite edges of a rail base constructed with an arm engaging the upper surface of the rail base at one side of the rail and an element so engaging said part at the other side of the rail as to press said

arm upon the rail base by a twisting action 50 upon said part.

13. A rail stay comprising a rail gripping element engaging top and bottom surfaces of a rail base at one side and the base edge at the other side of the rail and a torsion 55 producing rail base engaging part engaging said gripping element at its base edge engaging end.

14. An anticreeper comprising a rail engaging and clamping element constructed to 60 engage opposite edges of the rail base and the upper surface of the rail base at one side of the rail, a torsion producing part engaging said element and the rail at the side opposite to said arm and tie engaging 65 means acting upon said element.

15. A rail anchor comprising a cross bar constructed with a rail edge engaging arm at one end and a rail base engaging jaw at the other end thereof and a tie plate constructed to engage said arm and the upper 70 surface of the rail base at one side of said arm and the lower surface of the rail base and said arm at the other side of said arm to maintain said arm in spaced relation to 75 the tie and produce and maintain torsional stresses in said bar.

16. A device for preventing the creeping of rails comprising a cross bar having rigid 80 abutments adapted to engage and clamp the opposite edges of a rail and an arm at one end of said cross bar arranged to engage the upper surface of the rail base and a railway tie plate constructed to engage one end 85 of said cross bar.

17. An anticreeper comprising a tie plate and a cross bar engaging said tie plate at one side of the rail and provided with a shoulder and an arm at one end said arm being engaged by the tie plate and a shoulder and an arm adapted to engage the upper 90 surface of the rail base at the other end said shoulders engaging and gripping the opposite vertical edges of the rail base.
